UNITED STATES PATENT OFFICE

CLIFFORD I. PACKER, OF MERIDEN, CONNECTICUT, ASSIGNOR TO THE C. I. PACKER TOOL & DIE COMPANY, OF MERIDEN, CONNECTICUT, A CORPORATION

AUTOMATIC POLISHING MACHINE

Application filed January 16, 1930. Serial No. 421,148.

This invention relates to an improvement in automatic polishing machines, by which term is meant machines of the class designed to smooth or finish the surface of articles by grinding, buffing, burnishing, or other process.

The object of this invention is to provide a reliable, efficient machine of the character referred to, constructed with particular reference to convenience of operation and capacity for rapid production.

With the foregoing and other objects in view, my invention consists in a polishing machine comprising a body, a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; and a rotary chuck-driving member carried by the said body and located in position to engage and rotate a part of each of the said rotary chucks as the same are successively moved into a predetermined station by the intermittent movement of the said chuck-carrier.

My invention further consists in an automatic polishing machine characterized as above and having certain other details of construction and combinations of parts as will be hereinafter described and particularly recited in the claims.

35 In the accompanying drawings:

Fig. 1 is a view in side elevation of a polishing machine embodying my invention;

Fig. 2 is a top or plan view thereof;

Fig. 3 is a view corresponding to Fig. 2 but drawn on a larger scale and showing the plate-like chuck-carrier partly broken away;

Fig. 4 is a broken transverse sectional view taken on the line 4—4 of Fig. 3;

Fig. 5 is a similar but less comprehensive view taken on the line 5—5 of Fig. 3; and

Fig. 6 is a fragmentary sectional view taken on the line 6—6 of Fig. 3.

In carrying out my invention as herein shown, I employ a plate-like rotary chuck-carrier 10 formed in its under-face with a

right-angle bearing-groove 11 engaging the upper-face and periphery of an outturned bearing-flange 12 formed upon the upper edge of a cup-shaped body-member 13 resting in turn upon the upper edge of a similarly-shaped oil-chamber 14 to which it is secured by bolts 15.

The cup-shaped oil-chamber 14 has secured to its under side at equidistant points four (more or less) slightly-diverging supporting-legs 16 which have mounted between them, near their lower ends, a platform 17 supporting an electric motor 18, the shaft 19 of which is provided with a sprocket-pinion 20 connected by means of a sprocket-chain 21 to a sprocket-wheel 22 mounted upon the outer end of a main drive-shaft 23 projecting outward through the side-wall of the oil-chamber 14, as clearly shown in Fig. 1 of the drawings.

The rotary chuck-carrier 10 is held in place upon the bearing-flange 12 of the frame-member 13 by a retaining-ring 24 bearing against the under-face of the said flange 12 and secured to the under-face of the edge of the said chuck-carrier by screws 25.

Centrally secured to the under-face of the chuck-carrier 10 by means of an annular series of bolts 26 is an intermittent drive-plate 27 provided with an integral upstanding positioning-dowel 28 entered into an axial socket 29 formed in the chuck-carrier 10.

The intermittent drive-plate 27 forms a feature of a step-by-step drive-mechanism commonly known as a "Geneva movement" and, as shown, is formed upon its periphery with twelve (more or less) semicircular locking-notches 30 formed in a corresponding number of radial arms 30^a and flanked on their respective opposite sides by radial drive-notches 31 adapted to receive a driving-pin 32 upstanding from an arm 33 radially-offsetting from a locking-plate 34 which is of substantially cylindrical form conforming in curvature to the curvature of the locking-notches 30 of the plate 27 and formed upon one side with a concave clearance-notch 35, all in the well-known manner of the so-called "Geneva movement."

The locking-plate 34 is mounted upon the

upper end of a short vertical shaft 36 journalled in and passing vertically through the bottom-wall 37 of the cup-shaped body-member 13. The lower end of the shaft 36 is provided with a worm-wheel 38 meshing into a worm 39 upon the drive-shaft 23 before referred to, intermediate the ends thereof.

The drive-shaft 23 is mounted in bearing-blocks 40 and 41 depending from the under-face of the bottom-wall 37 of the body-member and projects outward, as before described, through the periphery of the oil-chamber 14, which is provided at this point with a stuffing-box 42 to prevent the escape of oil.

The inner end of the drive-shaft 23 mounts a miter-gear 43 meshing into a similar gear 44 mounted upon a shaft 45 extending at a right angle to the drive-shaft 23 and mounted in bearing-blocks 46 and 47 secured to the underface of the bottom-wall 37 of the body-member 13.

Near its outer end the shaft 45 mounts a chuck-driving worm 48 and at its opposite end is provided with a miter-gear 49 meshing into and driving a similar gear 50 mounted upon a shaft 51 extending parallel with the drive-shaft 23 and mounted at its respective opposite ends in bearing-blocks 52 and 53 secured to the under-face of the bottom-wall 37 of the body-member 13.

Near its right-hand end, as viewed in Fig. 3, the shaft 51 mounts a chuck-driving worm 54 and near its opposite end mounts a miter-gear 55 meshing into a similar gear 56 mounted upon the inner end of a short shaft 57 extending at a right angle to the shafts 23 and 51 and mounted in bearing-blocks 58 and 59 secured to the underface of the bottom-wall 37 of the body-member 13. The said shaft 57 mounts intermediate its ends and between the bearing-blocks 58 and 59 a chuck-driving worm 60 corresponding in function as will hereinafter appear, to the worms 48 and 54 before referred to.

The chuck-carrier 10 is formed in its upper-face, near its periphery, with twelve (more or less) vertical sockets 61, each of which receives the shank 62 of one of a corresponding number of rotary chucks 63 herein requiring no detailed description other than to say that each is provided with a plurality of gripping-jaws 64 which are adapted to expand to grip an article 65 to be ground or polished under the control of a vertical plunger 66 projecting from the lower end of each of the said chucks.

To provide for the rotation of each of the chucks as they successively reach positions in line with those occupied by three buffing or grinding-wheels 67, 68 and 69, in their step-by-step bodily movement with the chuck-carrier 10, as will hereinafter appear, I provide each of the said chucks at the lower end of its shank 62 with a spur-pinion 70.

When each of the twelve (more or less) rotary chucks 63 reach stations in line with the buffing or grinding-wheels 67, 68 and 69, it is desired to rotate them so as to rotate the work with respect to the said wheels. For this purpose I provide three corresponding driving-mechanisms respectively driven by the worms 60, 54 and 48 before referred to. A description of one of these driving-mechanisms will serve for the three since they all bear corresponding reference characters.

Each driving-mechanism includes a worm-wheel 71 secured to the lower end of a vertical shaft 72 rotating in a tubular bearing 73 at the free end of a pivotal arm 74 having its inner end mounted for oscillatory movement upon a stud 75 upstanding from the upper face of the bottom-wall 37 of the body-member 13.

The upper end of the shaft 72 carries a spur-gear 76 which is adapted to be successively engaged by the pinions 70 of the chucks 63 as the same are successively moved into engagement therewith during the step-by-step rotation of the chuck-carrier 10. Each of the arms 74 is held in engagement with a stop-screw 77 mounted in a block 78 secured to the upper face of the bottom-wall 37 of the frame-member 13, by a helical compression-spring 79 having one end seated against the said lever and its opposite end entering an adjustable spring-seat 80 mounted upon the inner end of an adjusting-screw 81 threaded into a bracket 82 secured to the upper-face of the bottom-wall 37 of the body-member 13.

In the operation of my improved polishing machine, the chuck-carrying plate is moved one-twelfth of a revolution for every revolution of the vertical shaft 36 which carries the locking-plate 34 and the driving-pin 32. This step-by-step rotation of the carrier 10 is effected by the counter-clockwise turning of the shaft 36 which causes the driving-pin 32 to enter one of the driving-notches 81 at the same time that the clearance-notch 35 is in position to clear the adjacent arm 30^a of the drive-plate 27, in which the semi-circular locking-notches 30 are formed.

As the locking-plate 34 continues its counter-clockwise rotation, it will lock the driving-plate 27 and hence the chuck-carrier 10 against movement in either direction after each successive one-twelfth turn has been imparted to it by the driving-pin 32—all in the manner of the well-known "Geneva movement."

As each of the chucks reaches a position where it is brought into engagement with one of the spur-gears 76 it will intermesh with the same, which is constantly driven through the main drive-shaft 23 and the chain of parts before described, so as to effect the rotation of the chucks 63.

If, when the pinion 70 makes contact with any one of the driving-gears 76, their teeth

are not in position to correctly intermesh, the arm 74 carrying the particular spur-gear 70 in question will yield in a clockwise direction against the counter-urge of its spring 79, so as to permit the proper meshing with the minimum of noise and without breakage.

As the chucks 63 reach a position substantially diametrically opposite the middle polishing-wheel 68, their plungers 66 will engage a segmental cam-plate 83 secured to the upper face of the bottom-wall 37 of the body-member 13 and provided with a rise 84 for lifting the said plungers and collapsing the jaws in any approved manner to release the work 65 already polished and to permit the application of a new piece of work to the chuck in question.

It will be seen from the foregoing that the several chucks are carried bodily around with the chuck-carrier 10 upon which they are mounted for relative rotation and that when they successively reach positions in line with each of the polishing-wheels 67, 68 and 69, they will have rotary movement imparted to them to more effectively present the surface of the article which they hold to the action of the said wheels and, further, that when they reach a position opposite the buffing-wheel 68 their jaws will be automatically caused to release their grip upon the article previously polished to permit its removal and to permit the mounting of a fresh piece of work to be subjected to the action of the polishing-wheels.

I claim:

1. In a machine of the character described, the combination with a body; of a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; a yielding bearing carried by the said body; a rotary chuck-driving member mounted in the said yielding bearing in position to be engaged by and to rotate a part of each of the said rotary chucks as the same are successively moved into a predetermined station by the intermittent movement of the said chuck-carrier.

2. In a machine of the character described, the combination with a body; of a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; a gear carried by each of the said rotary chucks; a yielding bearing carried by the said body; and a chuck-driving gear mounted in the said yielding bear-

ing in position to be meshed into by and to rotate a part of each of the said rotary chucks as the same are successively moved into a predetermined station by the intermittent movement of the said chuck-carrier.

3. In a machine of the character described, the combination with a body; of a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; a gear carried by each of the said rotary chucks; a plurality of yielding bearings carried by the said body in spaced relation to each other and at substantially equidistant points from the center of rotation of the said chuck-carrier; and a chuck-driving gear mounted in each of the said yielding bearings in position to be meshed into by and to rotate the gear of each of the respective rotary chucks as the same are successively moved into a predetermined station by the intermittent movement of the said chuck-carrier.

4. In a machine of the character described, the combination with a body; of a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; a swinging arm pivotally carried by the said body; a stop for limiting the swinging movement of the said arm in one direction; spring-means normally urging the said arm toward the said stop; and a rotary chuck-driving member mounted in the said swinging arm in position to be engaged by and to rotate a part of each of the said rotary chucks as the same are successively moved into a predetermined station by the intermittent movement of the said chuck-carrier.

5. In a machine of the character described, the combination with a body; of a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; a gear carried by each of the said rotary chucks; a swinging-arm pivotally carried by the said body; a stop for limiting the swinging movement of the said arm in one direction; spring-means normally urging the said arm toward the said stop; and a chuck-driving gear mounted in the said arm in position to be meshed into by

and to rotate the gear carried by each of the respective rotary chucks as the same are successively moved into a predetermined station by the intermittent movement of the said chuck-carrier.

6. In a machine of the character described, the combination with a body; of a chuck-carrier mounted upon the said body with capacity for step-by-step rotation with respect thereto; means for imparting step-by-step rotary movement to the said chuck-carrier; an annular series of work-holding chucks mounted upon the said chuck-carrier with capacity for individual rotary movement with respect thereto; a yielding bearing carried by the said body; a rotary chuck-driving member mounted in the said yielding bearing in position to be engaged by and to rotate a part of each of the said rotary chucks as the same are successively moved into a predetermined station by the intermittent movement of the said chuck-carrier; and means carried by the said body for engagement with the said chucks to automatically release the grip of the same upon the work as the same are successively moved into a predetermined station.

In testimony whereof, I have signed this specification.

CLIFFORD I. PACKER.
